OLSON & BEAR LLP(57) **CLAIM**

The ornamental design for a ship, as shown and described.

DESCRIPTION

FIG. 1.1 is a top, front, and right side elevated perspective view of a ship, embodying the design;

FIG. 1.2 is a left side plan view thereof;

FIG. 1.3 is a right side plan view thereof;

FIG. 1.4 is a top plan view thereof;

FIG. 1.5 is a rear plan view thereof;

FIG. 1.6 is a front plan view thereof;

FIG. 1.7 is a top, rear, and left side elevation perspective view thereof;

FIG. 1.8 is a top, front, and left side elevated perspective view thereof; and

FIG. 1.9 is a top, rear, and right side elevated perspective view thereof.

The broken lines illustrate portions of the ship that form no part of the claimed design.
